US00D969701S

(12) **United States Design Patent** (10) Patent No.: **US D969,701 S**
(45) Date of Patent: **** Nov. 15, 2022**

(54) **VEHICLE FRONT BUMPER PLATE**

(71) Applicant: **GM GLOBAL TECHNOLOGY OPERATIONS LLC**, Detroit, MI (US)

(72) Inventor: **Gary W. Ruiz**, Royal Oak, MI (US)

(73) Assignee: **GM Global Technology Operations LLC**, Detroit, MI (US)

(**) Term: **15 Years**

(21) Appl. No.: **29/783,026**

(22) Filed: **May 11, 2021**

(51) LOC (13) Cl. **12-16**

(52) U.S. Cl.

USPC **D12/196**

(57) **CLAIM**

The ornamental design for a vehicle front bumper plate, as shown and described.

DESCRIPTION

FIG. 1 is a front and left perspective view of a vehicle front bumper plate showing my new design;

FIG. 2 is a front elevation view of the vehicle front bumper plate of FIG. 1;

FIG. 3 is a left elevation view thereof;

FIG. 4 is a right elevation view thereof;

FIG. 5 is a top view thereof;

FIG. 6 is a back elevation view thereof; and,

FIG. 7 is a bottom view thereof.

The broken lines in the drawings depict portions of the vehicle front bumper plate that form no part of the claimed design.

1 Claim, 7 Drawing Sheets
